UNITED STATES PATENT OFFICE.

GEORGE LEEWORTH, OF CHICAGO, ILLINOIS.

LOCK-GAGE.

1,114,894.

Specification of Letters Patent. Patented Oct. 27, 1914.

Application filed May 19, 1914. Serial No. 839,527.

To all whom it may concern:

Be it known that I, GEORGE LEEWORTH, a citizen of the United States of America, and a resident of Chicago, in the county of Cook, 5 State of Illinois, have invented certain new and useful Improvements in Lock-Gages, of which the following is a specification.

This invention relates to that class of gages employed in making the position of 10 the key-holes and knob-shank orifices on the doors of houses and like structures. And the present improvement has for its object to provide a simple and efficient structural formation and combination of parts in a 15 gage adapted to afford a ready and accurate adjustment of parts to suit sizes and makes of door locks, and which in addition provides means for accurately making the position of the mortise for the lock casing with 20 relation to the key-hole and knob-shank hole markings on the sides of the door, all as will hereinafter more fully appear.

In the accompanying drawings:—Figure 1, is a side elevation, with parts broken away 25 and with parts in section, of a lock-gage embodying the present invention. Fig. 2, is a rear elevation of the same. Fig. 3, is a front elevation of the same.

Similar reference numerals indicate like 30 parts in the several views.

Referring to the drawings, 1 and 2 represent the respective main sections or members of the gage, which are slidably connected together in any usual and suitable manner, 35 preferably by means of a flat tongue 3 on one member, sliding in a correspondingly formed guide groove 4 in the companion member, as shown in Fig. 1.

5 is an adjusting screw-shaft journaled in 40 the member 1, and having screw-threaded engagement with a nut formation 6 in the other member 2, so that by its rotation the two members can be adjusted in relation to each other, as required.

45 7 is a gage plate overlapping the front end of the member 1 and secured thereto in a laterally adjustable manner by guide lugs 8, elongated slots 9 and clamping screws 10. The back of said plate 7 is preferably provided with top and bottom scales 11 so that 50 said plate may be accurately set with relation to the sides of member 1, and alternately to one side and the other of the same, and its vertical edges used as a guide for a 55 pencil or a scribe in marking the position of the lock-mortise in the edge of a door.

12 is a pair of heads adapted to move in vertical guide recesses 13, in the member 2, and carrying prick pins 14 on their respective sides for effecting markings in the door 60 corresponding with the key-hole and knob-shank orifice which are to be formed in the door. Each head 12 is provided with a screw-threaded shank 15 which is engaged by an individual thumb-nut 16 journaled in 65 the member 2 by an annular collar on said nut turning in a complementary recess formed therefor in the member 2, as shown in Fig. 1, so that by a manual rotation of said nuts, the prick pins 14 can be adjusted 70 to the proper points corresponding with the centers of the key-hole and knob-shank opening of the lock case intended to be placed in the particular door. The member or section 2 aforesaid, is preferably formed 75 in two plate shaped portions or halves secured together by screws or other usual fastening means, as illustrated in Figs. 1 and 2, and each portion or half will be provided with elongated slots through which the 80 aforesaid prick pins 14 pass.

A scale 17 will preferably be used in connection with each prick pin 14, for convenience in adjusting the same.

In a practical use of the appliance, the 85 prick points 14 are adjusted by their associated thumb nuts 16, to the vertical spaced relation which exists between the centers of the key and knob shank holes of the lock which is to be applied to the door. A like 90 adjustment is effected of said points 14, by the adjusting screw 5, to the horizontal relation which exists between the front edge of the lock and the above mentioned centers of the key and knob shank holes of the lock. 95 The gage plate 7 is also adjusted laterally by means of the elongated slots and clamping screws 9, 10, to cause one edge of the plate to extend beyond the body of the appliance, a distance equal to one-half the 100 thickness of the door. With such adjustments effected, the overlapping gage plate 7 is made to abut against the edge of the door at the proper height, and the markings of the prick points 14 effected in the side of the 105 door, and with the appliance still in position markings upon the edge of the door and along the one side edge and the top and bottom edges of the gage plate 7 are made, for the guidance of the workman in forming 110 and positioning the mortise recess in the door which receives the body of the lock.

Having thus fully described my said invention, what I claim as new and desire to secure by Letters Patent, is:—

1. In a lock gage, the combination of a pair of members slidably connected together, means for adjusting said members in relation to each other, a gage plate secured to the front of one member and overlapping the same, and a pair of adjustable prick pins carried by the other member, substantially as set forth.
2. In a lock gage, the combination of a pair of members slidably connected together, a screw-shaft associated with said members and adapted to effect an adjustment between said members, a gage plate secured to the front of one member and overlapping the same, and a pair of adjustable prick pins carried by the other member, substantially as set forth.
3. In a lock gage, the combination of a pair of members slidably connected together, means for adjusting said members in relation to each other a transversely adjustable gage plate secured to the front of one member and overlapping the same, and a pair of adjustable prick pins carried by the other member, substantially as set forth.
4. In a lock gage, the combination of a

pair of members slidably connected together, means for adjusting said members in relation to each other, a gage plate secured to the front of one member and overlapping the same, a pair of heads slidably mounted in the other member of the gage and carrying prick pins on their opposite sides, and means for effecting vertical adjustments of said heads, substantially as set forth.

5. In a lock gage, the combination of a pair of members slidably connected together, means for adjusting said members in relation to each other, a gage plate secured to the front of one member and overlapping the same, a pair of heads slidably mounted in the other member of the gage and provided with prick pins on their opposite sides and with screw-threaded shanks, and thumb nuts journaled in said other member and having operative engagement with said screw-threaded shanks, substantially as set forth.

Signed at Chicago, Illinois, this 16th day of May, 1914.

GEORGE LEEWORTH.
